HAT CREESE SHAPE HOLDER

Henry H. Hanson, Tyler, Tex.

Application September 8, 1947, Serial No. 772,788

2 Claims. (Cl. 223—84)

1

This invention relates generally to garment forms, and more particularly to a shape retainer for a hat comprising a wire form having portions shaped to fit between the sweat band and the front and rear portions of the crown, another portion joining these front and rear portions of the form and adapted to fit within the creases in the crown of the hat, together with a second form adjustably securable to the first form and adapted to retain the sides of the crown with the preferred creases therein.

A primary object of this invention is to provide a shape retainer for a hat which can be manufactured from very light wire stock, and which will have sufficient rigidity to properly retain the hat in shape.

Another salient object of this invention is to provide a hat shape retainer which is made in two sections, each of which is a wire form, and the second section being adjustably securable to the first section so that the shape of the creases, or style of creasing the hat may be changed, this versatility being achieved in part by reason of the resilient character of the wire forms.

Still another object of this invention is to provide a shape retainer in which one part of the retainer comprises front and rear portions joined by crown portions, and to make the front and rear portions adjustable as to length, so that the height of the crown of the hat wherein this invention is used may be altered.

Still another object of this invention is to provide a shape retainer for a hat which may be used to preserve the hat in correct shape during long periods of time of non-use, as well as for use as an easily removable shape retainer which may be retained in the hat during the use thereof, if desired.

And a last object to be specifically mentioned is to provide a hat shape retainer which is relatively inexpensive and practicable to manufacture, extremely simple to use, and which will give generally efficient and durable service.

With these objects definitely in view, as well as with other objects which will become apparent as this description proceeds, this invention resides in certain novel features of construction, combination and arrangement of parts and portions as will be hereinafter described in detail in the specification, and particularly pointed out in the appended claims, and illustrated in the accompanying drawings which form a material part of this application, and in which:

Figure 1 is a perspective view of a hat illustrating the type of creases which this invention

2

is adapted to retain in the crown portion of the hat;

Figure 2 is a perspective view of the complete shape retainer;

Figure 3 is a vertical longitudinal sectional view of a hat with this invention applied thereto, and with the part of the invention hereinafter referred to as the transverse member being shown as adjusted to an intermediate position and with the size of the loops and ends of this transverse member adjusted to minimum size, portions of the figure being shown in elevation, and other portions being shown in dash lines to better indicate the position of the crown portions of the form within the crown of the hat;

Figure 4 is a transverse vertical sectional view, taken on the line 4—4 in Figure 3, portions of the hat and the shape retainer being shown in elevation, and other portions which are hidden being shown in dash lines, to amplify the disclosure of this invention and to facilitate the illustration thereof.

Figure 5 is a view of the shape retainer with the transverse member positioned differently and the parts hereinafter described as crown portions bent into substantially semi-circular form, as when used to hold a "pork pie" or flat ringed crown form or the like.

Similar characters of reference designate similar or identical parts and portions throughout the specification and throughout the several views of the drawings.

Referring now to the drawings in detail, it will be noted that the environment wherewith this invention is adapted to be used includes a hat 10 having a brim 12, a crown which for purposes of this specification will be considered as comprised of the front portion 14, a rear portion 16 and a top portion 18 which is longitudinally creased so that a portion thereof assumes a position indicated in Figure 3, together with side portions 20 which will also be creased as indicated, and a sweat band 22. The shape retainer which comprises the subject matter of this invention includes a wire form having a front portion 24, a rear portion 26 and crown portions 28 joining the front and rear portions, together with a transverse member comprised of a pair of loops 30 joined by the bridge members 32 and 34.

It will be noted that the transverse member is formed from a single length of wire and that the ends of this wire overlap and are formed with small loops 36, thus forming the bridge member 34 with two strands of wire, to increase the rigidity thereof in order to better retain the

creased portion 18 of the crown in the hat. Each of the bridge members 32 and 34 is bent downwardly arcuate and the upper and outer ends of the bridge members are each sharply bent as at 38 so as to grip the crown members 28. The crown members 28 are each formed with notch bends 40 regularly spaced along an intermediate portion slightly forward of the center of each crown portion 28. These notch bends 40 facilitate the securement of the bent portions 38 of the transverse member to the crown portions 28, and also serve to definitely locate the transverse member in correct relation to the crown portions. Obviously, the transverse member is selectively engageable in these notch bends.

The front portion 24 and the rear portion 26 are each similar, except that the front portion 24 will preferably be considerably smaller than the rear portion. The single strand of wire used to construction the front portion 24, rear portion 26 and the crown portions 28 will be constructed of wire stock which will retain a shape after being forcibly bent into that shape and the substantially vertical parts 42 are each formed with a substantially V-shaped portion 44, so that the lengths of the vertical parts 42 may be shortened or lengthened by closing or opening the arms of the portions 44, as by bending the wire manually. It should be carefully noted that the wings 46 in the front portion 24 and the wings 48 in the rear portion 26 are each bent to conform with the curvature of the base of the crown of the hat, and are adapted to fit within the sweat band 22. The angularly disposed portions 50 extend from the outer ends of the wing portions 46 and are formed with bent portions at the upper ends thereof comprising slide bearings 52 associated with the upper portions of the substantially vertical parts 42. It will thus be seen that adjustment of the portions 44 will be automatically accompanied by a sliding movement of the slide bearing members 52 with reference to the parts 42. The portion 54 extending between the slide bearings 52 prevents undue divergence of the crown members 28.

The operation of this invention will be clearly understood from the foregoing description of the mechanical details thereof, taken in connection with the above recitation of the objects sought to be achieved by this invention. It may be further added, however, that the preferred method of securing the retainer in place includes the following steps. The sweat band 22 is first turned outwardly and the front portion 24 is inserted into the hat, the length of the vertical part 42 may then be adjusted, if required. The sweat band at the front of the hat is then turned into place and the front portion 24 clasped between the sweat band and the crown of the hat. If the front portion 14 of the crown has now been shaped according to the height desired, the procedure is completed by similarly adjusting and inserting the rear portion 26, the rear portion of the sweat band 22 being, of course, snapped back into position to retain the device in place. The transverse member may be adjusted to different positions in the different detents 40 and the bent portions 38 of the bridge portions 32 and 34 may be placed in different detents on each of the crown members 28. It will be obvious

that when the adjacent bent portions 38 on the transverse member are spaced apart, the size of the loops 30 on each side of the hat will be varied, and the shape of the crease in the sides 20 of the hat will be varied both as to size and position, by the use of this invention. Obviously, the change in the length of the vertical parts 42 will also change the general shape of the crown. It will be clear that the shape of the loops 30 may be slightly varied according to individual taste.

In the modified form of this invention illustrated in Figure 5, the crown portions corresponding to portions 28 are right-angularly bent, as at 56, and the portions 58 of these crown portions are bent into more nearly semi-circular form. This shape should be considered a modification which may be conveniently accomplished by the user of the device, as the same wire retainer is used. The shape described immediately above is used to retain the shape of "pork pie," flat ringed and other similar crown shapes. The other parts of the retainer are not necessarily altered for this last mentioned use.

Many minor variations may be made in the details of construction of this invention, and it is desired to limit the scope of this invention only in accordance with a proper interpretation of the term used in the appended claims.

Having described the invention, what is claimed as new is:

1. A shape retainer for a hat comprising a wire form including a front portion, crown portions shaped to lie within the creases in the crown of a hat, and a rear portion, said front and rear portions depending from said crown portions, and a transverse member having loops at each end and a reduced central portion comprising bridge members adjustably secured to said crown portions.

2. A shape retainer for a hat comprising a wire form including a front portion, crown portions shaped to lie within the creases in the crown of a hat and having oppositely disposed spaced notch bends, and a rear portion, said front and rear portions depending from said crown portion, and a transverse member having loops at each end and having a reduced central portion comprising bridge members selectively secured in said notch bends in said crown portions the loops being adjustable as to size by placing said bridge members in adjacent or non-adjacent pairs of opposite notch bends.
